CLAIM

We claim the ornamental design for a PCR multi-well plate, as shown and described.

DESCRIPTION

FIG. 1 is a top plan view of the PCR multi-well plate of the present invention;

FIG. 2 is a front view of the PCR multi-well plate of FIG. 1; FIG. 3 is a back side view of the PCR multi-well plate of FIG. 1;

FIG. 4 is a right side view of the PCR multi-well plate of FIG. 1;

FIG. 5 is a left side view of the PCR multi-well plate of FIG. 1;

FIG. 6 is a bottom view of the PCR multi-well plate of FIG. 1; FIG. 7 is a top plan view of a portion of the PCR multi-well plate of FIG. 1 shown without the rest of the plate for convenience of illustration;

FIG. 8 is a front view of the portion of the PCR multi-well plate of FIG. 7, the rear view being an identical image thereof shown without the rest of the plate for convenience of illustration;

FIG. 9 is a right side view of the portion of the PCR multi-well plate of FIG. 7, the left side being an identical image thereof shown without the rest of the plate for convenience of illustration;

FIG. 10 is a bottom view of the portion of the PCR multi-well plate of FIG. 7 shown without the rest of the plate for convenience of illustration; and,

FIG. 11 is a cross-sectional view of the portion of the PCR multi-well plate of FIG. 7, taken along line 11—11 shown without the rest of the plate for convenience of illustration.
